UNITED STATES PATENT OFFICE.

ALONZO O. ARMOUR, OF DALTON, GEORGIA.

GASOLENE-GUN.

1,192,839.

Specification of Letters Patent.

Patented Aug. 1, 1916.

Application filed March 11, 1916. Serial No. 83,586.

To all whom it may concern:

Be it known that I, ALONZO O. ARMOUR, a citizen of the United States, residing at Dalton, in the county of Whitfield and State of Georgia, have invented certain new and useful Improvements in Gasolene-Guns, of which the following is a specification.

This invention relates to an improved gun or cannon and the principal object of the invention is to provide a cannon which is so constructed that gasolene or a similar substance may be used as the explosive for driving the shell out of the barrel.

Another object of the invention is to provide a cannon so constructed that a tight closure will be provided at the inner end of the barrel when the shell is in place thus providing an air-tight combustion chamber in which the gas will be exploded to drive the shell out of the barrel.

Another object of the invention is to provide a cannon of the type described which will be very simple in construction and strong and durable.

This invention is illustrated in the accompanying drawings, wherein:—

Figure 1 is a view showing the improved cannon in section, and Fig. 2 is a fragmentary sectional view showing the manner of holding the asbestos packing in place in the inner end portion of the barrel.

This gun or cannon 10 is provided with a breech 11 communicating with the combustion chamber 12 which in its turn communicates with the barrel 13 having the usual rifling 14. Adjacent the inner end of this barrel there is provided a seat 15 in which is placed a packing 16 of asbestos or some other fire-proof material, the packing being held in place by means of the band 17 countersunk in the packing and held in place by the securing screws 18 which are also countersunk as clearly shown in Fig. 2. Therefore when the projectile 19 is inserted and the breech 11 closed, an air-tight combustion chamber will be provided. The supply pipe 20 which communicates with the combustion chamber may lead to a suitable reservoir or tank carrying gasolene or

some other highly combustible fluid. A valve 21 is positioned intermediate the length of the supply pipe 20 and is of the three-way type so that when turned to the position shown in Fig. 1, the gasolene may pass into the combustion chamber 12 and when turned to the proper position, compressed air may pass through the valve from the air supply pipe 22 into the combustion chamber through the pipe 20. After combustible fluid has been fed into the combustion chamber and the compressed air then also fed into this combustion chamber, the valve can be turned to shut off the flow from both pipes. A very highly combustible fluid will now be provided in the combustion chamber which when exploded will drive out the projectile. In order to explode this combustible mixture, there is provided a spark plug 23, a suitable circuit 24 being provided for the spark plug. It will thus be seen that after the projectile has been put in place and the gasolene and compressed air mixed in the combustion chamber, the switch 25 can be closed thus causing the spark which will explode this combustible mixture and drive the shell out of the barrel.

What is claimed is:—

1. In a gun of the character described, a combustion chamber having a barrel leading therefrom, the inner end portion of the barrel being provided with a cutout forming an annular seat, a packing placed in said seat, and a securing strip for said packing countersunk therein.

2. A gun of the character described including a combustion chamber having a barrel leading therefrom, and a packing countersunk in the wall of the inner end portion of said barrel and releasably held in place.

3. A gun of the character described including a combustion chamber having a barrel leading therefrom, a releasable breech for the combustion chamber, a packing embedded in the barrel for forming a tight closure around a projectile positioned therein to provide an air-tight combustion cham-

ber when the projectile is in place, means for feeding a combustible fluid into said combustion chamber, and means for igniting the fluid in the combustion chamber.

5. 4. A gun of the character described including a combustion chamber having a barrel leading therefrom and a packing in the wall of the inner end portion of said

barrel for forming a tight closure around a projectile positioned therein.

In testimony whereof I affix my signature in presence of two witnesses.

ALONZO O. ARMOUR.
